(57) **CLAIM**

The ornamental design for a massage chair, as shown and described.

DESCRIPTION

FIG. 1 is a front elevational view of a massage chair showing the claimed design;

FIG. 2 is a rear elevational view of the massage chair;

FIG. 3 is a left side elevational view of the massage chair;

FIG. 4 is a right side elevational view of the massage chair;

FIG. 5 is a bottom plan view of the massage chair;

FIG. 6 is a top plan view of the massage chair;

FIG. 7 is a top front perspective view of the massage chair; and,

FIG. 8 is another top front perspective view of the massage chair.

The broken lines in the drawings depict portions of the massage chair that form no part of the claimed design.
